UNITED STATES PATENT OFFICE.

HERMAN W. FALK, OF MILWAUKEE, WISCONSIN, ASSIGNOR TO THE FALK COMPANY, OF MILWAUKEE, WISCONSIN, A CORPORATION OF WISCONSIN.

MEANS FOR OPERATING HYDROCARBON-BURNERS FOR METALLURGICAL FURNACES.

SPECIFICATION forming part of Letters Patent No. 757,606, dated April 19, 1904.

Application filed March 5, 1903. Serial No. 146,292. (No model.)

To all whom it may concern:

Be it known that I, HERMAN W. FALK, residing at Milwaukee, in the county of Milwaukee and State of Wisconsin, have invented 5 a new and useful Improvement in Means for Operating Hydrocarbon-Burners for Metallurgical Furnaces, of which the following is a description, reference being had to the accompanying drawings, which are a part of this 10 specification.

My invention has relation to improvements in means for operating hydrocarbon-burners for metallurgical furnaces.

Certain types of metallurgical furnaces are 15 supplied with oil fuel at opposite ends through the medium of oil-burners. The oil fuel is supplied in this class of furnaces first at one end and then at the other. Heretofore it has usually been necessary for two operators to 20 stand at opposite ends of the furnace, so that when the operator at one end thrusts the burner at that end into the furnace the operator at the other end must withdraw the burner at said end. A third attendant has 25 been required to be stationed at another point, so as to start the feeding of oil and air through the burner which is thrust inwardly and stop the feeding of the oil and air through the burner which is adjusted outwardly. In case 30 in the class of furnaces referred to only one attendant or operator is assigned for the work of thrusting one burner in and the other out it is necessary for him to first adjust one of the burners at one end and then walk to the 35 opposite end of the furnace for the purpose of adjusting the burner at that end. When the course first mentioned is pursued, it is obvious that the services of three men are required, while if the second course is pursued 40 much time is lost by the attendant in walking from one end of the furnace to the other.

The primary object of my invention is to provide a construction whereby one man at a given point can not only govern the adjusting 45 inwardly of the burner at one end of the furnace and the adjusting outwardly of the burner at the opposite end of said furnace, or vice versa, but can also at the same time start the

flow of oil and air through the burner which is adjusted inwardly and stop the flow of oil 50 and air through the burner which is adjusted outwardly.

A further object contemplated by the invention is the provision of improved means for adjusting the burners so as to direct the 55 discharge of oil and air therefrom and onto the contents of the furnace at any desired angle.

With the above and other incidental objects in view the invention consists of the devices 60 and parts or their equivalents, as hereinafter set forth.

In the accompanying drawings, Figure 1 is an elevation of a metallurgical furnace, showing my improved hydrocarbon-burners in connection therewith. Fig. 2 is a view of the mechanism for operating the oil-burners and which is located in front of the furnace. Fig. 3 is an enlarged detail view of one of the burners and means for supporting said burner and 70 permitting it to travel; and Fig. 4 is a detail view looking in front of the traveling roller, with the rails of the track in section.

Referring to the drawings, the numeral 5 indicates an ordinary form of metallurgical 75 furnace. The openings for the introduction of the hydrocarbon fuel are located, respectively, at opposite ends of the furnace, as most clearly shown in Fig. 1. Extending from opposite ends of the furnace at an inclination are parallel rails 6, forming a track for the travel of a grooved roller or trolley 7. The inner ends of the rails of each track are connected by a cross-bar 8, which cross-bar is pivoted to a bracket 9, secured to the 85 end of the furnace. The outer end of the track is suspended in any desirable manner, but is preferably hung on a rod 10, depending from a ceiling, beam, or rafter 11 in such manner that the outer end of the track is 90 raised, and hence said track is on a gradual decline from its outer end inwardly. The rod is preferably of two parts connected by a turn-buckle 12, engaging right and left hand threads on the respective sections of the rod. 95 By turning this turnbuckle the track may be

adjusted at the desired inclination. To permit the turnbuckle to be readily operated for the purpose of shortening or lengthening the rod, the upper section of said rod is pivotally connected to the ceiling or rafter 11 and the lower end thereof pivotally connected to the track. The trolley or wheel 7 is provided with a grooved periphery adapted to receive the upper and lower rails of the track and to travel thereon and therebetween. Suspended from the axis or shaft 13 of this wheel is an arm 14, the upper end thereof being preferably forked, as most clearly shown in Fig. 4, and the forked portion straddles the wheel, so that the bifurcate arms through which the shaft 13 passes are on each side of the wheel. The lower end of this arm is formed or provided with a socket 15. This socket is split, as most clearly shown in Fig. 4, and the split portions are brought closer together or farther apart by means of a screw 16, provided with a suitable operating-handle 17.

Each hydrocarbon-burner (indicated by the numeral 18) has projecting upwardly therefrom a ball 19, which fits in the socket 15, and thereby forms a universal-joint connection between the hydrocarbon-burner and the arm 14, whereby the burner is permitted to be swung in any direction. Also straddling the wheel and mounted on the shaft 13 thereof are arms 20, which are united at their lower ends and provided at said point of union with a screw-threaded opening through which a set-screw 21 passes and bears at its inner end against the arm 14. The arms 20 are advisably extended outwardly and upwardly at an incline from the shaft 13, as indicated by the numerals 22 22, and carry between their outer ends a small grooved roller 23, which bears against the upper rail of the track. This forms a point of resistance for the screw 21 when said screw is turned. If the set-screw is turned inwardly, it is obvious that its inner end acts on the arm 14 in such manner as to swing the lower end of said arm in the arc of a circle inwardly, and consequently raise the hydrocarbon-burner, while if the screw is turned in the opposite direction said arm will swing in the arc of a circle outwardly, and consequently lower the hydrocarbon-burner. By this means an attendant who may stand at one end of the furnace can raise or lower the burner to suit requirements. The outer end of each burner is fitted with a valve 24, which enables the attendant who may be at the end of the furnace where said burner is located to regulate at that point the quantity of oil flowing into the burner.

The track, burner, and other parts just described are duplicated at the opposite end of the furnace, as clearly shown in the drawings, and corresponding parts are indicated by the same reference-numerals.

Located at a convenient point near the furnace, and preferably in front thereof, is the

mechanism for operating the burners—that is, for thrusting one burner into the furnace and the other burner out of said furnace, and vice versa, and for causing the flow of oil and air through one burner and stopping the flow of oil and air through the other burner, and vice versa. The burners are operated in the manner indicated by means of counterweighted ropes or cables. These ropes or cables are indicated by the numerals 25 25, and each is secured at one end to the flooring and is then extended below said flooring and around a pulley 26 of a counterweight 27, thence upwardly through the flooring and over a guide-pulley 28, thence along and over another guide-pulley 29, thence 70 downwardly and beneath a pulley 30, journaled in a projection from the outer end connecting-piece 31 of the rails 6, and finally connected to the arm 14. In Fig. 2 of the drawings the right-hand cable is shown as 80 broken away below the flooring, and it is to be understood, therefore, that the counterweight of this cable is in a lowered position, and hence the said cable is pulled downwardly and the right-hand oil-burner pulled out from 90 the furnace. The left-hand cable, however, is raised, and the left-hand burner has therefore been permitted to travel inwardly into the furnace. If now it is desired to change the burners—that is to say, cause the right-hand burner to travel inwardly and the left-hand burner to travel outwardly—the right-hand cable is slackened or pulled upwardly against the action of the counterweight, and as the end of this cable is secured to the arm 95 100 14 it is evident that the roller 7 is thereby permitted to travel down the inclined track, and hence carry the burner into the furnace. The left-hand cable, however, is pulled downwardly, and this necessarily pulls the left-hand 105 burner outwardly.

For regulating the supply of oil I provide at a desirable point, preferably in close proximity to the cables, an oil-inlet pipe 32, leading from any suitable source of oil-supply 110 and extending to and communicating with an upright pipe 33, which upright pipe in turn communicates with a horizontal pipe 34, said horizontal pipe being controlled by means of a three-way valve 35, provided with a suitable 115 operating-handle 36. From one end of the horizontal pipe 34 extends a pipe 37, which leads to the left-hand oil-burner. From the opposite end of said horizontal pipe extends another pipe, 38, which leads to the right-hand burner. Each of these pipes 37 and 38 is provided with a valve 39 and 40, respectively, for regulating at this point the flow of oil 120 through said pipes. The air is supplied through an air-supply pipe 41, leading from any suitable source of air-supply and connecting with an upright pipe 42. The upper end of this upright pipe connects with a horizontal pipe 43, which horizontal pipe is controlled by means of a three-way valve 44, op- 125 130

erated by means of a suitable handle 45. Extending from one end of the horizontal pipe 43 and leading to the left-hand oil-burner is a pipe 46. Extending from the opposite end 5 of said horizontal pipe 43 and leading to the right-hand oil-burner is a pipe 47. The quantity of air flowing through the pipes 46 and 47 is controlled by means of valves 48 and 49, arranged in the respective pipes. In the operation of this mechanism for supplying the burners with oil and air if, for instance, the burners are in the position shown in Fig. 1 it is necessary under such adjustment of the burners to cut off the supply of oil and air to 15 the right-hand burner and cause a flow of oil and air through the left-hand burner. This is accomplished by turning the three-way valve in a direction to shut off the flow of oil through the pipe 38 and permitting said oil 20 to flow through pipe 37, and consequently through the left-hand oil-burner. At the same time the three-way valve controlling the air-supply is turned in a direction to permit the air to flow through pipe 46 and to shut off 25 pipe 47. If now the adjustment of the burners is reversed—that is to say, the left-hand burner is adjusted outwardly and the right-hand burner inwardly—the three-way valves of the respective oil and air supply 30 pipes are turned in a direction to cut off pipe 37 and open up pipe 38, so as to allow the oil to flow to the right-hand burner, and to cut off air-pipe 46 and open up pipe 47, so as to permit the air to flow to said right-hand burner.

From the foregoing description it will be seen that I provide a simple form of mechanism for obviating difficulties which have heretofore existed in supplying the metallurgical furnaces with oil fuel and that by my improvements the oil-burners are readily regulated from one point and at the same time the supply of oil and air to the burners is also regulated at said point. Furthermore, I provide a simple means for adjusting the burner at any angle so as to direct the oil and air discharged therefrom onto the fire at the point where it is most desirable that the jet should issue. This is accomplished by the provision of the ball-and-socket connection between the arm 14 and the burner. It is also desirable that the hydrocarbon-burners should be raised or lowered to suit requirements, and this is readily regulated in my invention by manipulating the set-screws 21.

While I have herein described the invention as particularly applicable to oil-burners and for use in connection with metallurgical furnaces, yet I do not wish to be understood as limiting myself thereto, inasmuch as the invention may be applicable to burners for feeding any other kind of fuel and also adapted for use in other kinds of furnaces or heating devices. I also do not wish to be understood as restricting myself to two burners lo-

cated adjacent to two openings of the furnace, inasmuch as a single burner may be utilized and operated in the manner or substantially the manner described without departing from the spirit and scope of my invention, and the mechanism for causing said burner to move inwardly or outwardly and for supplying the fuel to the burner may be omitted altogether or only one of such mechanisms may be employed or both mechanisms may be omitted altogether, and these variations I would also consider as within the spirit and scope of my invention.

What I claim as my invention is—

1. In means for operating burners for furnaces, the combination of a furnace provided with an opening, a rail extending from the furnace, a carriage adapted to travel on said rail, a burner carried by the carriage, means for permitting an angular adjustment of the burner, and means for causing the carriage to travel inwardly on the rail so as to carry the burner to the opening of the furnace.

2. In means for operating burners for furnaces, the combination of a furnace provided with an opening, a rail extending from the furnace and arranged on a gradual incline outwardly, a carriage adapted to travel on said rail, a burner carried by said carriage, means for holding the carriage and the burner carried thereby in an outwardly-adjusted position on the rail, and means for permitting the carriage to travel inwardly on the rail by its own weight so as to carry the burner to the opening of the furnace.

3. In means for operating burners for furnaces, the combination of a furnace provided with an opening, an inclined rail, means for adjusting the inclination of said rail, a carriage adapted to travel on the rail, a burner carried by said carriage, means for holding the carriage and the burner carried thereby in an outwardly-adjusted position on the rail, and means for causing the carriage to travel inwardly on the rail so as to carry the burner to the opening of the furnace.

4. In means for operating burners for furnaces, the combination of a furnace provided with an opening, a rail pivotally connected at its inner end to the furnace, a suspending means for the outer end of the rail, means for adjusting said suspending means so as to provide for the inclination of the rail, a carriage adapted to travel on said rail, a burner carried by the carriage, means for holding the carriage and the burner carried thereby in an outwardly-adjusted position on the rail, and means for causing the carriage to travel inwardly on the rail so as to carry the burner to the opening of the furnace.

5. In means for operating burners for furnaces, the combination of a furnace provided with an opening, a rail pivotally connected at its inner end to the furnace, a pivotally-suspended rod, pivotally connected at its lower

end to the outer end of the rail, said rod consisting of sections, a turnbuckle connecting the oppositely-threaded ends of said sections, and adapted when turned to shorten or lengthen 5 the rod, in order to provide for the proper inclination of the rail, a carriage adapted to travel on said rail, a burner carried by the carriage, means for holding the carriage and the burner carried thereby in an outwardly-adjusted position on the rail, and means for causing the carriage to travel inwardly on the rail so as to carry the burner to the opening of the furnace.

6. In means for operating burners for furnaces, the combination of a furnace provided 15 with an opening, a track extending from the furnace and consisting of parallel rails arranged one above the other, a carriage provided with a wheel or trolley arranged between and engaging the rails, and adapted to travel thereon, a burner carried by said carriage, means for holding the carriage and the burner carried thereby in an outwardly-adjusted position on the track, and means for 20 causing the carriage to travel inwardly on the track so as to carry the burner to the opening of the furnace.

7. In means for operating burners for furnaces, the combination of a furnace provided 30 with an opening, a rail extending from the furnace, a carriage adapted to travel on said rail, a burner having a turning connection with the carriage so as to provide for varying the angle of said burner, means for holding the burner in the position to which it is turned, means for holding the carriage and the burner carried thereby in an outwardly-adjusted position on the rail, and means for causing the carriage to travel inwardly on the 35 rail so as to carry the burner to the opening of the furnace.

8. In means for operating burners for furnaces, the combination of a furnace provided 45 with an opening, a rail extending from the furnace, a carriage adapted to travel on said rail, a burner having a universal-joint connection with the carriage, means, after the burner is turned on the universal-joint connection, for holding said burner at adjusted 50 position, means for holding the carriage and the burner carried thereby in an outwardly-adjusted position on the rail, and means for causing said carriage to travel inwardly on the rail so as to carry the burner to the opening of the furnace.

55 9. In means for operating burners for furnaces, the combination of a furnace provided with an opening, a rail extending from the furnace, a carriage adapted to travel on said rail, an arm depending from the carriage, a burner having a universal-joint connection with the depending arm, means after the burner is turned on the universal-joint connection for holding said burner at adjusted 60 position, means for holding the carriage and

the burner carried thereby in an outwardly-adjusted position on the rail, and means for causing said carriage to travel inwardly on the rail so as to carry the burner to the opening of the furnace.

70

10. In means for operating burners for furnaces, the combination of a furnace provided with an opening, a rail extending from the furnace, a carriage adapted to travel on said rail, a burner carried by said carriage, means 75 for holding the carriage and the burner carried thereby in an outwardly-adjusted position on the rail, means for causing the carriage to travel inwardly on the rail, so as to carry the burner to the opening of the furnace, and means for raising or lowering the burner.

11. In means for operating burners for furnaces, the combination of a furnace provided with an opening, a rail extending from the 85 furnace, a carriage adapted to travel on said rail, an arm turnably depending from the carriage, another arm extending from the carriage and provided at its lower end with a screw-threaded opening, a set-screw turning through said opening and against the turnable arm, a burner connected to the turnable arm, means for holding the carriage and the burner carried thereby in an outwardly-adjusted position on the rail, and means for 90 causing the carriage to travel inwardly on the rail so as to carry the burner to the opening of the furnace.

12. In means for operating burners for furnaces, the combination of a furnace provided 100 with an opening, a track extending from the furnace, said track consisting of parallel rails arranged one above the other, a roller or trolley between said rails and engaging the same, a shaft or axis for said roller or trolley, an 105 arm movably depending from the shaft or axis, another depending arm provided in its lower portion with a screw-threaded opening, and also provided with an extension projecting from its upper end, the extremity of said extension carrying a roller bearing against the upper rail of the track, a set-screw turning through said screw-threaded opening and against the movable depending arm, a burner connected to the movable depending arm, 110 means for holding the carriage and the burner carried thereby in an outwardly-adjusted position on the track, and means for causing the carriage to travel inwardly on the track so as to carry the burner to the opening of the furnace. 115

13. In means for operating burners for furnaces, the combination of a furnace provided with an opening, a rail extending from the furnace, a carriage adapted to travel on said rail, a burner carried by the carriage, means for 125 raising and lowering the burner, means for swinging said burner in different directions, means for holding the carriage and the burner carried thereby in an outwardly-adjusted position on the rail, and means for causing the 130

carriage to travel inwardly on the rail so as to carry the burner to the opening of the furnace.

14. In means for operating burners for furnaces, the combination of a furnace provided with an opening, a rail extending from the furnace, a carriage adapted to travel on said rail, a burner carried by the carriage, and a counterweighted cable connected to the carriage and normally holding said carriage and the burner carried thereby outwardly, but permitting said carriage and burner to move inwardly, when the cable is slackened.

15. In means for operating burners for furnaces, the combination of a furnace provided with openings at two points, burners arranged near the openings, and mechanisms for controlling said burners and arranged adjacent to each other and at a desired distance from the furnace, each of said mechanisms constructed, when operated in one way, to permit the burner to move inwardly to the opening of the furnace, and when oppositely operated to cause the burner to be drawn outwardly.

16. In means for operating burners for furnaces, the combination of a furnace provided with openings at two points, rails extending from the furnace at points near the openings, carriages adapted to travel on said rails, burners carried by the carriages, and mechanism for controlling the carriages and arranged adjacent to each other and at a desired distance from the furnace, each of said mechanisms constructed when operated in one way to permit the carriage controlled thereby and the burner carried by the carriage to move inwardly to the opening of the furnace, and when oppositely operated to cause the carriage and the burner carried thereby to be drawn outwardly.

17. In means for operating burners for fur-

naces, the combination of a furnace provided with openings at two points, burners arranged near the openings, mechanisms for controlling said burners and arranged adjacent to each other and at a desired distance from the furnace, each of said mechanisms constructed, when operated in one way, to permit the burner to move inwardly to the opening of the furnace, and when oppositely operated to cause the burner to be drawn outwardly, fuel-supply mechanism, and means for causing the fuel-supply mechanism, when operated in one way, to supply fuel to the burner which is moved inwardly, and to stop the supply of fuel to the burner which is moved outwardly, and vice versa, when operated in the opposite way.

18. In means for operating burners for furnaces, the combination of a furnace provided with openings at two points, burners arranged near said openings, mechanisms for controlling the burners and arranged at a desired distance from the furnace, each of said mechanisms when operated in one way adapted to permit the burner controlled thereby to move inwardly, and when operated in the opposite way to be drawn outwardly, fuel-supply mechanism arranged at a desired distance from the furnace, and means for causing the fuel-supply mechanism, when operated in one way, to supply fuel to the burner which is adjusted inwardly, and stop the supply of fuel to the burner which is adjusted outwardly, and vice versa, when operated in the opposite way.

In testimony whereof I affix my signature in presence of two witnesses.

HERMAN W. FALK.
